UNITED STATES PATENT OFFICE.

GEORGE BANKER, OF PITTSBURGH, PENNSYLVANIA.

VALVE FOR FLUSH-TANKS.

1,162,209.

Specification of Letters Patent. Patented Nov. 30, 1915.

Application filed April 23, 1915. Serial No. 23,372.

To all whom it may concern:

Be it known that I, GEORGE BANKER, a citizen of the United States, and whose post-office address is 1714 Morningside road, 5 Pittsburgh, Pennsylvania, have invented certain new and useful Improvements in Valves for Flush-Tanks, of which the following is a specification.

This invention relates to new and useful 10 improvements in valve for flush tanks and the like and more especially that class generally known as ball valves.

The object of the invention resides in the provision of a ball valve having a flange at 15 the lower end thereof for engaging the valve seat thus at all times insuring the proper engagement of the same for sealing the tank to which the device is applied against leakage.

20 A further object of the present invention resides in the provision of a valve of the above specified type which will be comparatively simple and inexpensive to manufacture, reliable and efficient in use, and readily 25 operated.

With the above and other objects in view the present invention resides in the novel 30 features of construction, formations, combinations and arrangements of parts to be hereinafter more fully described, claimed and illustrated in the accompanying drawing, it being understood that various minor 35 changes in the specific details of construction can be resorted to within the scope of the appended claim without departing from the spirit or sacrificing any of the advantages of the invention.

In the accompanying drawing forming a part of this application: Figure 1 is a side 40 elevation of the invention. Fig. 2 is a vertical sectional view thereof, and Fig. 3 is an enlarged fragmentary section showing the ball valve and its seat.

Referring to the accompanying drawing 45 by similar characters of reference throughout the several views, 5 designates generally a casting which is adapted to be threaded into the bottom of the flush tank in the usual manner. This casting 5 is provided with a supporting flange 6 adapted to engage the upper side of the tank bottom

and a lateral extension 7 which communicates with the interior of the said casting 5 and affords a means for supporting the usual overflow pipe 8. A bracket 9 is adjustably secured to the overflow pipe 8 and has an inner terminal bearing sleeve 10 in which the valve stem 11 is slidably located. The upper extremity of the casting 5 is flared outwardly as at 12 and then curved inwardly as at 13 forming a valve seat for engagement with the valve 14 carried by the lower end of the valve stem 10.

The valve 14 is globular in formation and comprises an upper semi-spherical section 15 provided with a lower annular locking flange 16 adapted to engage the upper locking flange 17 formed upon the lower section 18 of the valve 14. A curved bottom 19 having a lower concaved surface 20 is provided upon the section 18 and projects beyond the lower end thereof as shown at 21 for engagement with the valve seat 13 to the outer surface to which the same conforms. Obviously as the valve 14 is lowered the same will at all times be guided into proper engagement with its seat 13 preventing the contents of the flush tank from flowing therefrom through the above described casing 5.

From the foregoing it will be manifest 80 that a valve is provided which will fulfil all of the necessary requirements of such a device.

Having thus fully described my invention what I claim as new and desire to protect by Letters Patent is:—

In a valve such as described, the combination of a casting having a flared upper end and an inwardly extending upwardly inclined flange forming a valve seat, a ball 90 valve movable to and from said valve seat, said ball valve having a bottom the lower edge of which extends below the valve and the lower side of which is concaved conforming to the shape of the valve seat, and means 95 for supporting the valve.

In testimony whereof I affix my signature in the presence of two witnesses.

GEORGE BANKER.

Witnesses:

Wm. M. DUFF,
JOHN BANKER.
